UNITED STATES PATENT OFFICE.

HENRY F. MOORE, OF CHICAGO, ILLINOIS, ASSIGNOR, BY MESNE ASSIGNMENTS, TO
W. S. SAITER, OF CHICAGO, ILLINOIS.

MECHANISM FOR TRANSMITTING MOTION.

1,113,039.

Specification of Letters Patent.

Patented Oct. 6, 1914.

Application filed May 5, 1913. Serial No. 765,594.

To all whom it may concern:

Be it known that I, HENRY F. MOORE, a citizen of the United States, and a resident of Chicago, in the county of Cook and State 5 of Illinois, have invented certain new and useful Improvements in Mechanism for Transmitting Motion, of which the following is a specification.

This invention relates to a device which 10 is used to move the horizontal members of a grate, at determined intervals, and the object of the invention is to obtain a device which, by automatically actuating said movable members, will automatically supply 15 coal to a grate, will automatically stoke said grate at determined intervals, and will permit the manual stoking of said grate between said intervals.

A further object is to obtain a device 20 which is economically constructed and easily installed, and usable in a large variety of differently constructed heating and steam generating plants; which requires but little care and attention to operate it; which 25 does not require a person to be particularly skilled in mechanics to use and care for it; which is durable; not liable to break or get out of order; and slightly in appearance.

In the drawings accompanying and forming 30 a part hereof Figure 1 is a front elevation of a boiler front and of mechanism embodying this invention attached thereto. Fig. 2 is a side elevation of the operating mechanism which is illustrated in Fig. 1, 35 and showing the upper end of a grate mechanism actuated thereby. Fig. 3 is a side elevation of a cam forming an element in the operating mechanism of the device. Fig. 4 is a front elevation of the lower end of a 40 lever which forms an element in said operating mechanism. Fig. 5 is a side elevation of the lever which is illustrated in Fig. 4. Fig. 6 is a top plan view of a sliding member which forms an element of said operating 45 mechanism. Fig. 7 is a side elevation of said sliding member and Fig. 8 is a front elevation thereof. Fig. 9 is a side elevation of an additional sliding member, and of a hook which is pivoted thereon, and Fig. 10

50 is an elevation of the sliding member which is illustrated in Fig. 9. Fig. 11 is a sectional view on line 11—11 of Fig. 12, viewed in the direction indicated by the arrows, and Fig. 12 is a front elevation of the guide

which is illustrated in section in Fig. 11. 55 Fig. 13 is a front elevation of a boiler front and of a modification of the mechanism embodying this invention. Fig. 14 is a side elevation of the modification which is illustrated in Fig. 13; and Fig. 15 is a side elevation of said modification, viewed at an angle of 180° from Fig. 14.

A reference character applied to designate a given part indicates said part throughout the several figures of the drawings, wherever 65 the same appears.

X is the front wall of a boiler and X' the door of said front wall.

A, (Fig. 2) are supporting members of a grate which is provided with horizontal 70 tables B, water supply pipes C, and horizontally movable members D, E, and connections e.

F is a rocking shaft which is journaled in 75 bearings a on supporting members A.

d is a link which is pivotally attached at one of its ends to movable member D and at the other end to one of the arms of bell crank G. Members D are provided with slots d', and d'' are bolts in slots d'. Horizontal movement of members E is obtained by means of connections e. The advanced position of the horizontal movable member E is indicated by the broken lines E' in Fig. 2. 80

The mechanism embodying this invention is designed to automatically obtain, at regular, and not too frequent, intervals, a rocking of the shaft F, (said shaft F forming an element in said mechanism). 85

H is a guide secured to the front of the boiler to which the device is attached; I, I' are the separable parts of a sliding head which is movably mounted in said guide H; i is an abutment on part I of said head, and i' is a pivoted hook on part I' of the head. Hook i' engages with the abutment i to join 90 said parts I and I' together. 95

J is a rotating crank shaft journaled in bearings J'. 100

j is a crank arm on shaft J, and j' is a gear wheel on said shaft J. J'' is a driving shaft and j'' is a gear wheel on said shaft J'', intermeshing with gear wheel j'.

K is a connection extending from crank 105 arm j to head I and pivotally connected to said head by pivot k.

L is a link pivotally attached at its ends

to one arm of bell crank G and to part I' of the two part head.

M is a lever pivoted at m on bracket Y.

N is a cam on shaft n, and N' is a ratchet wheel on said shaft.

O is a dog or pawl.

P is a bell crank attached to bracket y by pivot p. Pawl O is pivotally mounted on bell crank P. Said bell crank P is actuated 10 in one direction by abutment p' on gear wheel j', and in the other direction by the weight of the horizontal arm of said bell crank.

The lower end of connection K moves 15 up and down once to each revolution of crank shaft J, and moves part I of the two part head in guide H. Cam wheel N is attached to shaft n to rotate therewith, and said shaft is moved in a step by step movement by pawl O engaging with the ratchet teeth of wheel N', as said bell crank P is moved by abutment p'.

In the construction illustrated in Figs. 1 and 2, the pawl O gives one impulse to 25 wheel N', shaft n and wheel cam N, on each revolution of wheel j'. Additional impulses to said wheel, shaft and cam wheel are given by placing additional abutments on the side of wheel j', if desired. Connection L is moved upward by the upward movement of part I' of the two part head, and said part I' is moved upward by part I of said head when the hook i' thereon is in engagement with the projection i on part I. 30 I'' is a spring which yieldingly holds the hook i' out of engagement with abutment i. Hook i' is forced into position to engage with projection or abutment i by the lower end of lever M, when said lever is moved by 35 cam wheel N, (provided said lower end is in operative position.) m' is the lower end of lever M and is pivotally attached to the body part of lever M by pivot m''. End m' can be turned on its pivot so as not to engage 40 with hook i', (see broken lines in Fig. 4), and when it is so turned the movement of head I does not move head I'. When said end m' is in position to force hook i' against projection or abutment i it is rigidly maintained in place by butterfly nut M'. Where 45 a plurality of these devices, and of grates, are installed under a plurality of boilers, or in the case of a very large boiler under a single one, the crank shaft J may be extended to operate the horizontally movable members of all said grates, which does away 50 with the necessity of more than one of said crank shafts. Where a plurality of horizontally movable grate members are installed in a battery of boilers an individual crank shaft J may be used for each set of 55 said horizontally movable members, if desired. Shaft F is manually operated between the times of the automatic operation thereof, if necessary; and when a banking

of the fire is desired the automatic operation of the device is cut out by turning the end m' out of operative position, as hereinbefore described.

In the modification which is illustrated in 70 Figs. 13, 14 and 15, the crank shaft J is

provided with the crank j, and at its opposite end is also provided with a crank Q. Crank Q is provided with roller q. Crank Q performs the functions of projection or 75 abutment p', (illustrated in Figs. 1 and 2).

P' is a pivotally mounted lever which is provided with the pawl or dog O'. Ratchet wheel N' is rotated in a step by step movement by means of pawl O', lever P' and crank Q, on the revolution of the shaft J, in the same manner as said ratchet wheel is rotated in the hereinbefore described construction by means of pawl O.

In this modification the about to be described construction is substituted for lever M' and its appurtenances, to automatically obtain the engagement at stated intervals of the hook i' with projection or abutment i.

Hook i' is provided with the arm i'' which rests on the pivoted lever R. Said lever R is pivoted on one side of guide H, by pivot r. Arm S is pivoted to bracket y by pivot S', so as to rest on the cam wheel N' and to be actuated 80 as the cam of said cam wheel passes thereunder.

Lever S is connected to the lever R by connection T. t is a spring which is interposed between connection T and arm S, to obtain what may be termed a take up motion; that is, permitting the arm S to move 85 on its pivot more than the arm or lever R is allowed or required to move on its pivot.

U, Fig. 14, is a spring, one end of which abuts against the bracket u and the other end against the arm or lever P', yieldingly holding said lever P' in its determined initial position.

u' is a rod or bolt extending through bracket u and spring U, and pivotally attached to arm P'; and said rod or bolt is provided with the take up nuts u'.

By means of said take up nuts the return movement of said arm P' is determined, and thereby the number of teeth on ratchet wheel N' with which the pawl O' engages on 90 its forward movement is adjustably controlled.

V, V', Figs. 13, 14, are arms which are rigidly attached to shaft F, to form the bell crank which is substituted in this modification for the bell crank G, in Fig. 2.

V'' are broken lines indicating a portion of a lever which may be inserted in a pocket or socket which is provided therefor in arm V.

Lever V'' is used to manually operate the shaft F to actuate horizontal members D and E.

I claim:—

1. In mechanism for transmitting motion to a horizontally movable grate member, the combination of said horizontal member, a crank shaft, means to rotate said crank

shaft, a head, a connection between said crank shaft and said head, an additional head, a rigid hook on said first named head and a movable hook on said additional head, 5 said movable hook adapted to co-act with said rigid hook, means to yieldingly hold said hooks out of engagement, a cam, a lever, said lever adapted to force said movable hook into engagement with said rigid hook 10 when actuated by said cam, and a connection between said additional head and said horizontally movable grate member.

2. A horizontally movable member, a crank shaft, a head comprising separable 15 parts, guides to said parts, means to join said parts together, and mechanism interposed between said crank shaft and said joining means to operate said joining means at determined intervals, in combination with 20 a rock shaft, arms rigidly attached to said rock shaft to form a bell crank, a connection between said crank shaft and one of the parts of said head, a connection between the other part of said head and one of the arms 25 forming said bell crank, and a connection between the other arm of said bell crank and the horizontally movable member of a grate.

3. A horizontally movable member, a

crank shaft, a head comprising separable parts, guides to said parts, means to join 30 said parts together, and mechanism interposed between said crank shaft and said joining means to operate said joining means at determined intervals, said interposed mechanism comprising a lever, a pawl on 35 said lever, a ratchet wheel actuated by said pawl, a connection between said crank shaft and said lever, a cam wheel connected to said ratchet wheel to be operated thereby, an additional lever between 40 said cam wheel and said joining means, said additional lever adapted to be actuated by said cam wheel and to operate said joining means, and a rock shaft, in combination with arms rigidly attached to said rock shaft to 45 form a bell crank, a connection between said crank shaft and one of the parts of said head, a connection between the other part of said head and one of said arms to said bell crank, and a connection between the other 50 arm to said bell crank and the horizontally movable member of a grate.
